UNITED STATES PATENT OFFICE.

GEORGE GASS BRITTON, OF ANNISTON, ALABAMA, ASSIGNOR TO INTERSTATE ROOFING & FOUNDRY COMPANY, OF ANNISTON, ALABAMA, A CORPORATION OF ALABAMA.

SASH-OPERATING MECHANISM.

1,091,728.

Classification of Letters Patent. Patented Mar. 31, 1914.

Application filed August 30, 1913. Serial No. 787,446.

To all whom it may concern:

Be it known that I, GEORGE GASS BRITTON, a citizen of the United States of America, residing at Anniston, in the county of Calhoun and State of Alabama, have invented certain new and useful Improvements in Sash-Operating Mechanism, of which the following is a specification.

My invention relates to certain improvements in sash operating mechanism.

One object of my invention is to utilize a floating lever connected at one end to a swinging link and at the other end to a sash operating connection and which is pivotally connected at an intermediate point to an axially movable line shaft which rocks it to open and close the sash.

A further object of my invention is to so arrange and design the lever and its several connections that the line shaft acts with strong and effective leverage thereon at all points so that the full force and effect of the power applied to the line shaft is available for operating the sash in all positions.

A further object of my invention relates to the central power station which operates the line shafts, and it contemplates a novel means for connecting the racks with the line shaft so that the power station may be readily taken down and moved to any desired point along the shafting without requiring the latter to be disconnected or dismounted.

A further object of my invention relates to the novel construction of the brackets for the line shafts and to the fastening means which attach the floating levers to the line shafts, permitting the lever to be readily attached to and disconnected from the shaft as well as adjusted along the same.

My invention further comprises the details of construction and arrangement of parts, which in their preferred embodiment, are hereinafter more particularly described and claimed, reference being had to the accompanying drawings which form a part of this specification, and in which:

Figure 1 is a plan view of my sash operating mechanism, the parts being shown in full line position, with the sash closed, and in dotted line position with the sash open.

Fig. 2 is a front elevation of Fig. 1. Fig. 3 is a detail view of the bracket for the line shaft. Fig. 4 is a side view of the central power station, and Fig. 5 is a front elevation of Fig. 4. Fig. 6 is a detail perspective view of the means for detachably connecting the racks to the line shafts. Fig. 7 is a perspective view showing the manner of mounting the floating levers on the line shafts. Fig. 8 is a detail perspective view of the lever supporting clamp.

Similar reference numerals refer to similar parts throughout the drawings.

I have illustrated my invention as adapted to open and close sashes but the principles underlying its construction are available for operating doors, sky-lights, shutters, etc.

As illustrated, the sash 1 is pivotally connected to the mullions or frame 2 and adapted to swing outwardly and upwardly to open. I attach, preferably to the inner face of the mullions, a series of brackets 3 for supporting the line shafts 4 and 5 which shafts are disposed one above the other and extend lengthwise of the series of sashes to be operated. The bracket 3 is preferably formed by a bent metal frame, the lower member 6 thereof being flanged at its outer end and connected by a bolt or pin 7 to the main section 3 of the bracket. The bracket is braced to better support the weight of the line shafts by a diagonal brace 8 and it is provided with a series of alining openings in the top and bottom sections which are adapted to receive pins 9. These pins extend vertically down through the bracket and are held in position therein by cotter keys 10. On each pin I mount two concave rollers 11 which are spaced by a rotatable sleeve or pipe section 12. The line shafts are received between the adjacent pairs of rolls and supported thereby free for longitudinal movement. To each bracket I attach a plate 13 which projects on each side of the outer end of the bracket and has its outer ends bent down into a horizontal plane and perforated to form the lugs 14. To each of these lugs is pivoted a horizontally swinging link 15. Each link is disposed inwardly.

Figure 1 is a plan view of my sash operating mechanism, the parts being shown in full line position, with the sash closed, and in dotted line position with the sash open.

toward the adjacent sash and preferably projects beyond the center of such sash and is pivotally connected at its outer end by a pin 16 and cotter key 17 to what I term the outer end of a floating lever. These levers are all similar in construction and I prefer to use two to operate each sash. For the sake of clearness, the levers operated by the upper line shaft 4 are designated as 18, and 10 those operated by the line shaft 5, as 19. It will be noted that the levers are bent at an angle in a horizontal plane and that the two levers for operating a given sash are reversely disposed and have their shorter and 15 outer ends connected to the swinging links 15 that are connected to the brackets on each side of such sash.

The inner and longer ends of the levers are pivotally connected at their inner ends 20 to the sash operating links 20 by means of pins 21 which are perforated to receive cotter keys. At their elbows the floating levers are pivotally connected by pins 22 to clamps which are adjustably mounted on the line 25 shafts. These clamps (see Figs. 7 and 8) comprise a main body portion 23 which is provided with a tapering groove into which a wedge section 24 of the clamp is adapted to be inserted endwise and locked. The 30 wedge has one edge 25 which works in a groove overhung by the outer inturned edge 26 of the section 23, while its opposite side is provided with a tongue 27 which works in a correspondingly shaped undercut groove formed in the side wall of the 35 slot in section 23. The abutting faces of these sections have semi-circular grooves which register and jointly form a circular opening 28 to receive a line shaft. The 40 tapered character of the wedge permits it to be forced inwardly into the tapered slot until the clamp tightly grips the shaft. An opening 29 is drilled down through the two sections of the clamp and receives a pin 22 45 which thereby serves to both hold the clamp sections locked on the shaft and to pivotally connect a floating lever to the clamp. A set screw 30 is screwed in through the back of clamp section 23 and holds the clamp 50 in set position on the line shaft while a cotter key 31 detachably holds the pin 22 in operating position. By reference to Fig. 2 it will be noted that the clamps are 55 reversely connected to the line shafts 4 and 5 so as to bring their respective floating levers into position between the shafts. The outer ends of the operating arms 20 are pivotally connected to sashes at 32. A brace 46 is attached by pin 22 to each clamp 60 on the opposite side from the floating lever, and its free end is bent down and riveted to the long end of the lever to reinforce it.

The central power station, according to my invention, is adapted to be mounted at

any point along the line shafting and to be 65 readily detached and shifted to other points as occasion may require. As constructed, the power station is supported by a heavy metal bracket comprising upper and lower angled sections 33 which are suitably attached to a mullion and which, at their outer ends, are fastened to a vertical section 34. Parallel with section 34 is a bar 35 which has angled ends bolted to section 34 and to sections 33. These members 34 and 70 35 are provided with suitable bosses in which stub shafts 36 and 37 are mounted. The shaft 37 has fixed on its outer end a sheave wheel 38 and is held in position in the bracket by a washer 39 and a detachable 75 cotter key 40. A train of gears is mounted in the bracket and comprise a small pinion 41 on the shaft 37 which meshes with a large pinion 42 on the shaft 36 and this pinion, in turn, serves to drive a small pinion 43 disposed between and in mesh with two racks 44 and 45. These racks are similar in construction and, as seen in Fig. 6, are formed as integral parts of elongated boxings which open along one side to receive the line shaft and at each end are provided with enlarged housings 47 having openings facing the same side as the longitudinal slot in the boxing and also having openings on the back side. A detachable 95 clamp is adapted to be received in each of these housings 47 and, by engaging the end walls of the housing, to hold the racks against longitudinal movement on the shafts while permitting the boxing to be slipped 100 off the shaft over the clamps. The clamp comprises two similar hinged sections 48 which are fastened together at their free ends by a bolt 49. By reference to Fig. 4 it will be seen that the racks are held against 105 lateral disengagement from the shafts by the narrow clearance provided for them between the wheel 42 and the frame section 35. The racks are held in engagement with the pinion 43 by means of rollers 50 which 110 are journaled in the frame section 35. The bracket sections 33, like the brackets 3, are provided with a series of openings 51 which receive the bolts that hold the frame assembled.

A plate 13 carrying lugs 14, to which the two adjacent links 15 are attached, is bolted to section 35 of the power station bracket. A guard 52 for the sheave pulley is attached to the outer section 34 of the bracket and a chain 53 is passed over the pulley and is used to turn it, and, by the power augmenting train of gears shown, to rotate the driving gear 43 and move the racks and line shafts 4 and 5 in reverse directions. To remove the power station it is only necessary to disconnect the section 35 from the other part of the bracket frame, after loosening

the cotter keys which hold the shafts 36 and 37 journaled therein, and then to draw the main bracket frame and pulley outwardly. The racks are then free to be slipped off the line shafts and the clamps 48 thereon, after which the clamps are detached. The power station can be readily applied at any other point along the line shafting by transferring the bracket to the desired point and, after applying the clamps loosely in the boxings 47 and mounting the racks in the desired position on the shafts, assembling the bracket parts about the shafts and racks in the manner described after which the clamps are made fast. If desired the whole system of line shafting may be adjusted toward or from the sashes by means of the extra holes provided in the brackets to receive the shaft supporting members.

20 Power is applied by a chain 53 to revolve the sheave wheel, which, through the train of gears described, revolves the small pinion 43 that meshes with the racks 44 and 45 and cause the two line shafts 4 and 5 to be moved 25 longitudinally in reverse directions. The train of gears are designed to apply ample power to move the load on the shafts. As the line shafts are moved, for instance, to shift the floating levers 18 and 19 from full 30 line to dotted line position, Fig. 1, it will be noted that the angular travel of the inner end of the levers is small and that there is but small variation in the angle between the lever and link 15 in both positions, so that 35 the power of the line shaft is applied always approximately at right angles to the levers and I maintain thereby a highly effective application of the line shaft power to the work throughout all operating positions for 40 the mechanism. As shaft 4 is moved to the right the fulcrum point of the lever, namely, its pivotal connection to the free end of link 15, travels inwardly following the arcuate travel of the link. The travel of the inner 45 end of the floating lever, where it is connected to the operating arm 20, will be influenced by the movement of both its moving pivot at pin 22 and its fulcrum point at pin 16, with the result that it will move 50 bodily to the right and swing outwardly about its point, which movements jointly effect the opening of the sash with a push 55 which approaches a straight push as the sash opens and the floating lever assumes the dotted line position shown. Inasmuch as the lower shaft 5 has been moving in the opposite direction to shaft 4, a similar but reverse movement has been imparted thereby 60 to the floating lever 19 which it controls and the latter has been swung to its dotted line position and has acted on the other side of the sash to move it outwardly.

The connections for the operating elements are adjusted to apply the push and

pull strain evenly and to the desired extent 65 to both sides of the sash.

By the construction of my floating levers and the peculiar manner of mounting them I am enabled to avoid the loss of power which is common in other constructions 70 where the angle between the shaft and the sash operating lever practically disappears in certain operating positions.

It will be obvious that certain advantages of my construction are obtainable where a 75 single line shaft is used, this arrangement being used where the sashes are small. In this case the pivot 32 would be located at the center of the sash, only one lever to each sash being used when operating with a single 80 line shaft.

Without limiting myself to the details of construction hereinbefore set out, what I claim as new and desire to secure by Letters Patent, is:—

85

1. The combination with a pivoted member to be operated and its support, of an operating shaft which is longitudinally movable, a lever pivoted medially to said shaft and disposed crosswise of the shaft, 90 and two reversely disposed arms pivoted to the ends of the lever, one arm being pivoted to said support and the other arm to the member to be operated.

2. The combination with a pivoted member to be operated and its support, of an operating shaft which is longitudinally movable, a lever pivoted medially to said shaft and disposed crosswise of the shaft, 100 and two reversely disposed arms pivoted to the ends of the lever, one arm being pivoted to said support on one side of said member and the other arm to the other side of the member to be operated.

95

3. The combination with a series of pivoted sashes and their supports, of a longitudinally movable operating shaft, supports therefor, floating levers pivotally connected medially to said shaft, horizontally swinging links having a fixed support at one 110 end and having their free ends pivotally connected each to an outer end of a floating lever, and operating rods pivotally connected each to the inner end of a floating lever and to a sash to be operated thereby, substantially as described.

115

4. In a sash operating mechanism, two reversely movable operating shafts, fixed supports to confine said shafts to longitudinal movement, floating levers pivoted 120 medially to said shafts, swinging links having fixed supports at one end and which have their free ends pivotally connected to the outer ends of said levers, and operating rods which are pivotally connected to 125 the inner ends of said levers and to the sash to be operated, substantially as described.

125

5. The combination with a plurality of sashes to be opened and their supports, of a pair of longitudinally movable line shafts standing in front of said sashes, supports in which said shafts are independently movable, means to move said shafts simultaneously in opposite directions, floating levers which are pivotally connected medially to said shafts and disposed substantially at right angles thereto, links pivotally connected at one end to the sash supporting structure and having their free ends pivotally connected to the outer ends of said floating levers, and operating rods which are pivotally connected to the inner ends of the floating levers and to the sashes to be operated, substantially as described.
6. In combination, two line shafts, means to move said shafts longitudinally in reverse directions, a floating lever connected medially to each shaft in front of the sash to be operated, reversely disposed links adapted to loosely connect the outer ends of said levers to fixed supports on each side of the sash to be operated thereby, and operating rods adapted to pivotally connect the inner ends of said levers to the sash to be operated, substantially as described.
7. In combination with a pivoted sash and a structure in which it is mounted, of an operating mechanism for the sash comprising two reversely movable line shafts, supports which confine said shafts to longitudinal movement, a floating lever pivotally connected medially to each shaft, an operating rod which pivotally connects the inner end of each lever to the adjacent side of the sash, and a link which pivotally connects the outer end of each lever to the sash supporting structure at the opposite side of the sash from that to which the operating rod common to the same lever is connected.
8. A sash operating mechanism comprising operating rods pivoted to the sashes, longitudinally movable operating shafts, means to operate said shafts in reverse directions, levers pivoted medially to said shafts and inclined slightly from a right angle to said shaft in opposite directions, an operating rod pivotally connecting the inner end of each lever to the adjacent side of the sash, and a link pivotally connecting the outer end of each lever to a fixed support on the opposite side of the sash from that to which each lever is connected.
9. The combination with a plurality of pivoted sashes and a structure in which said sashes are mounted, of two line shafts, supports which confine said shafts to longitudinal movements, an operating mechanism adapted to impart reverse movements to said shafts, and an operating mechanism for each sash controlled by said shafts and comprising a pair of angled levers pivotally connected at their elbows to said shafts and

having their inner ends disposed at reverse angles to the shafts, links pivotally connecting the inner end of each lever to a sash, and links pivotally connecting the outer ends of each lever to the structure on the opposite side of the sash from that to which the lever is operatively connected, substantially as described.

10. In a sash operating mechanism, a longitudinally movable line shaft, a clamp detachably and adjustably mounted on said shaft comprising top and bottom members which make a wedge fit, each section comprising a semi-circular shaft opening, a vertical pin adapted to pass down through both clamp sections and interlock them, a floating lever which is pivoted to said pin, a set screw to hold the clamp in adjusted position on the shaft, a swinging fulcrum for one end of the lever, and a swinging operating connection from the other end of the lever to the sash.

11. In a sash operating mechanism comprising two line shafts, supports confining said shafts to longitudinal movements, and a central power station for operating said shafts and comprising a train of gears, and reversely disposed racks detachable sidewise from and adjustable lengthwise on said shafts, which racks are driven by said train of gears, substantially as described.

12. In a sash operating mechanism, a longitudinally movable line shaft, a support to confine said shaft to longitudinal movement, an operating mechanism for the shaft comprising a pinion and rack, said rack being bodily detachable sidewise from the shaft, and detachable means for holding the rack against movement on the shaft, substantially as described.

13. In a sash operating mechanism, a longitudinally movable line shaft, supports to confine said shaft to longitudinal movement, an operating mechanism for the shaft comprising a pinion and rack, said rack having a side slot adapted to receive said shaft and to permit the rack being detachable sidewise from the shaft, and means for detachably holding the rack on the shaft, substantially as described.

14. In a sash operating mechanism, a longitudinally movable line shaft, supports to confine said shaft to longitudinal movements, an operating mechanism for the shaft comprising a central power station having a revoluble pinion, a rack adapted for attachment to and disconnection from an intermediate point of said shaft without interference with the shaft supports on either side thereof, and means to detachably hold said rack in predetermined operating position on said shaft, substantially as described.

15. In combination, a plurality of elements to be simultaneously moved, a line

shaft extending lengthwise of said elements, a series of bearings for the shaft, a series of actuating mechanisms for transmitting shaft motion to said elements, and a central power station for operating the shaft comprising a bracket which is removable to different points along the shaft without disturbing the latter, power transmission means carried by said bracket, and means adapted to be engaged by said transmission

means to move the shaft, which means is also detachable from the shaft without disturbing it.

In testimony whereof I affix my signature in presence of two witnesses.

GEORGE GASS BRITTON.
